United States Patent Office

Des. 187,961
Patented May 17, 1960

187,961

BOX FOR A BOTTLE OR SIMILAR ARTICLE

John B. Lang, Minneapolis, Minn.

Application June 23, 1958, Serial No. 51,493

Term of patent 14 years

(Cl. D58—11)

The figure is a perspective view of a box for a bottle or similar article showing my new design.

The side not shown is the same as the side shown.

I claim:

The ornamental design for a box for a bottle or similar article, substantially as shown and described.
